INHALER

Huna L. Apfelbaum, Brooklyn, N. Y., assignor to
 Victor Metal Products Corporation, Brooklyn,
 N. Y., a corporation of New York

Application April 26, 1943, Serial No. 484,561

6 Claims. (Cl. 128—200)

1

This invention relates to inhalers and particularly to the type which is adapted to be molded throughout of suitable synthetic plastic material.

The invention contemplates the provision of a simple inhaler provided with a valve at each end and adapted to be easily manipulated, without removing any of the parts, to open both valves simultaneously and thereby to establish communication between the interior of the inhaler and the outside air.

The invention further contemplates the provision of a holder for medicament slidably in the interior of the inhaler and provided with opposed valves, one of which projects beyond the inhaler casing in the operative or open position thereof, and the other of which so projects in the inoperative or closed position thereof, the projecting valves forming the means by which the holder may be manipulated.

The invention further contemplates the provision of an inhaler having only three separable and moldable parts comprising a two-part casing and a holder for medicament together with co-operating valve parts thereon, and in which inhaler the casing parts need be separated only when the medicament therein is to be renewed, the inhaler being otherwise operable without such separation.

The invention further contemplates the provision of an inhaler adapted to be opened for use and closed by one hand of the user.

The various objects of the invention will be clear from the description which follows and from the drawing, in which

Fig. 1 is a vertical section of the inhaler taken on the line 1—1 of Fig. 2, showing the inhaler in its closed or sealed inoperative position.

Fig. 2 is a similar section taken on the line 2—2 of Fig. 1.

Fig. 3 is a partial front elevation and partial section of the inhaler in its open or operative position, showing the medicament in place in the holder therefor.

Fig. 4 is a horizontal section taken on the line 4—4 of Fig. 1.

Fig. 5 is a foreshortened perspective view of the medicament holder, the middle part of the holder being broken away for convenience of illustration.

In the embodiment of the invention shown by way of example, the inhaler casing consists of two preferably but not necessarily molded parts 10 and 11, the part 10 being in the nature of a cap and having an axial opening 12 in the end thereof, which opening is preferably used as a dis-

charge or outlet opening for the medicated vapor accumulating in the casing. An internally threaded enlargement 13 is provided at the lower end of the cap for the reception of the correspondingly externally threaded upper end 14 of the casing part 11. To prevent leakage of vapor between the parts, a washer or gasket 15 of any suitable compressible material such as cork, rubber, felt or the like is seated on the interior 10 shoulder 16 of the enlargement 13. At the lower end of the part 11 is made an axial opening which is preferably the inlet opening for outside air into the casing. Said opening has an enlarged outer portion 17 and a constricted inner 15 portion 18 for the purposes soon to appear.

Slidably mounted in the interior of the casing is the medicament holder 19. Said holder is also adapted to be molded of synthetic plastic and is in the general shape of an elongated O, being 20 provided with the teat-like axially arranged opposed and projecting valve stems 20 and 21. The medicament is inserted into or removed from the central space 22 of the holder when the cap 10 is removed, and may be carried by any suitable 25 known device intended for that purpose such as the elongated cartridge 23 (Fig. 3) or a wad of absorbent cotton.

The upper valve stem 20 is preferably tapered and molded integrally with the top of the holder 30 and has an annular recess or indent in the lower part thereof filled by a hollow resilient washer or gasket 24 of rubber, cork, felt or the like arranged to enter the discharge port or opening 12 and to be pressed into contact with the wall of 35 said opening when the holder is in its uppermost or valve port closing position to prevent leakage of vapor.

The lower valve stem 21 may be detachably or 40 permanently secured as desired to the lower end of the holder, but in the form shown, it is screwed thereto and terminates at its lower end in an enlargement such as the head 25 adapted to fit into the enlarged part 17 of the adjacent inlet opening. For adequately sealing the inlet opening 45 when the inhaler is not in use, a hollow washer or gasket 26 in the form of a flanged eyelet is provided. The flange of the washer 26 contacts with the top of the wall surrounding the enlarged part 17 of the inlet opening and the 50 cylindrical part of the washer engages the wall of the portion 18 of the opening when the holder is in its port closing position. There, the holder is at its uppermost limiting position in the casing, but the lower part of the holder is in sufficient 55 upward spaced relation to the bottom of the

casing part 11 to carry the inlet valve stem into its closed position, (Figs. 1 and 2) and the upper end of the valve stem 20 projects a substantial distance outwardly beyond the casing for access thereto by a finger or the thumb of the user.

To move the holder into the open or extreme lowermost position of Fig. 3, the user may grasp the casing in one hand and need merely press axially on the valve stem 20 with the thumb or finger of the same hand thereby sliding the holder downwardly and opening both valves simultaneously, the valve 21, 25 in this position projecting downwardly below the casing. As the user inhales the vapor from the opening 12, air entering the opening 17, 18 passes through the space 27 around the bottom of the holder to the spaces 28, 29 between the edges of the holder sides 30, 31 and the casing, then through the medicament 23 to become charged with vapor and then passes out through the opening 12. To again close the valve ports, the thumb or a finger of the hand which holds the inhaler may be used to push the valve 21, 25 axially, thereby to move the holder upwardly.

The lower end of the holder which connects the sides 30, 31 and which carries the valve stem 21, 25 is suitably shaped to engage the inner wall of the casing part 11 at a point spaced above the bottom of said wall when the holder is in its lowermost position, thereby insuring that a sufficient space 27 is provided above the inlet valve for the entrance of air into the casing through the open valve. The upper part of the holder which connects the sides 30 and 31 and which carries the valve stem 20 may be similarly shaped, said connecting parts of the holder preferably serving as stops to limit and define the extreme positions of the holder in the casing.

The outer surfaces of the holder sides 30 and 31 are shaped preferably to fit and conform to the inner walls of the casing in order to provide sufficient frictional engagement therebetween to maintain the holder in the extreme or limiting positions into which it is caused to slide without danger of accidental movement therefrom. However, if it is desired to additionally insure against such accidental or undesired movement, the middle parts of said holder as 32, 33 may be made of slightly larger diameter than the remainder thereof, and slightly larger than the diameters of the inner casing surface so that as the holder is originally inserted into the casing, the sides 30 and 31 thereof are somewhat compressed together, as is possible by reason of their spacing, length and consequent resiliency. The spring action so secured serves to cause the sides to resist any movement of the holder other than deliberate movement thereof.

It is unnecessary to remove the holder from the casing when the member 23 is to be removed or replaced. When the casing part 10 is removed, the upper half of the holder is exposed together with the upper half of said member 23, whereby the medicated member when in the form of a cartridge may easily be extracted from the space 22 by tilting it out of the holder. The removal of a cotton wad offers no difficulties. The cartridge is also dropped into place readily by tilting into the space 22. Should it become necessary to remove the holder for any reason, the valve 21, 25 may first be unscrewed from the holder whereupon the holder is easily lifted out of the lower casing part to which it is normally slidably attached.

From the above, it will be seen that I have provided an inhaler having a slidable holder capable of easy manipulation with one hand without disturbing the casing, that the inhaler is adapted to be molded of plastic material and is provided with opposed valves accessible from the outside and operating simultaneously and effectively to permit and prevent the discharge of vapor as desired.

Various modifications may be made in the illustrated embodiment of the invention without departing from the spirit thereof as defined by the appended claims.

I claim:

1. In an inhaler, a casing having an inlet opening at one end thereof and an outlet opening at the other end thereof, a hollow elongated member frictionally fitted into and slidable within the casing and having a pair of imperforate side walls arranged in transverse spaced relation to each other, a valve stem at each end of said member, one of said stems passing through the inlet opening and the other through the outlet opening, said stems sealing the openings in one position of the member and unsealing the openings in another position of the member, the member having an unobstructed space therein between the side walls and between the stems to hold medicament inserted thereto by a movement substantially parallel to said side walls.

2. In an inhaler, a casing having an upper cap-like hollow part and a lower hollow part, the upper part having an upper end provided with a valve-receiving opening therein, the lower part having a lower end provided with a valve-receiving opening therein, said upper part being open and internally threaded at its lower end, said lower part being open and externally threaded at its upper end for the detachably screwed and sealed connection thereof to said upper part, a flattened annular member elongated in a direction axially of the casing and slidably mounted within the casing and engaging the inner surfaces of the casing parts and guided by said surfaces, said surfaces being of uniform diameter, said member being of lesser width as measured in a selected direction than the diameter of said inner surfaces to arrange part of said member in inward spaced relation to said inner surfaces, and a valve stem projecting outwardly from each end of the member, the stem at one end being arranged coaxially of the opening in said upper part and having an enlargement thereon to seal and unseal the last mentioned opening, the stem at the other end also having an enlargement, at least one of the stems projecting through its cooperating valve-receiving opening beyond the casing in all positions of the member in the assembled casing, said stems, valve-receiving openings and enlargements being of lesser diameters than the diameter of said inner surfaces.

3. In an inhaler, a combined medicament holder and valve means comprising a pair of similar transversely spaced apart and elongated sides providing an unobstructed space therebetween for the insertion of medicament thereto by a movement in a transverse direction, a connecting portion joining each pair of the adjacent ends of said sides, and a valve stem projecting axially from each connecting portion, one of the stems being enlarged diametrically adjacent the connecting portion from which it projects and the other stem being enlarged diametrically at the end thereof 75 remote from the connecting portion from which it

projects, the inner ends of said stems terminating at the holder.

4. In an inhaler, a casing having an air inlet opening and a vapor outlet opening, and a generally O-shaped combined medicament holder and valve means for said openings slidably mounted within the casing and comprising a pair of transversely spaced sides each frictionally engaging the inner surface of the casing, a connecting portion integrally joining each pair of the adjacent ends of said sides, and a pair of valve stems each entering one of the respective openings and each projecting from one of the respective connecting portions.

5. In an inhaler, a casing having an air inlet opening and a vapor outlet opening, and a generally O-shaped combined medicament holder and

valve means for said openings slidably mounted within the casing, said combined holder and valve means including a pair of valve stems each entering one of the respective openings and projecting from opposite ends of the holder, one of the stems being diametrically enlarged at the outer end thereof and the other stem being diametrically enlarged at the inner end thereof.

6. In an inhaler, a slidable combined medicament holder and valve means of generally O-shaped form including a pair of axially opposed valve stems projecting outwardly from the ends of the holder, one of said stems having an enlargement at the inner end thereof, and the other of said stems having an enlargement at the outer end thereof.

HUNA L. APFELBAUM.
